UNITED STATES PATENT OFFICE.

ROY M. DEAN, OF CHICAGO, ILLINOIS.

HEATER FOR MOTOR-VEHICLES.

1,250,986.

Specification of Letters Patent. Patented Dec. 25, 1917.

Application filed December 14, 1916. Serial No. 138,853.

To all whom it may concern:

Be it known that I, ROY M. DEAN, a citizen of the United States, residing at Chicago, in the county of Cook and State of Illinois, have invented certain new and useful Improvements in Heaters for Motor-Vehicles, of which the following is a specification.

This invention relates to improvements in heaters for motor vehicles and the like and one of the objects of the same is to provide an improved device of this character embodying a radiator constituting a foot rest, and having a non-circulating water chamber therein, the water being heated by means of the exhaust gases from the engine, circulating through the radiator and out of commingling relation with the water in the water chamber.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating the invention and in which—

Figure 1 is a perspective view of an improved device of this character, constructed in accordance with the principles of this invention.

Fig. 2 is a vertical sectional view taken on the line 2—2, Fig. 3.

Fig. 3 is a vertical sectional view taken on the line 3—3, Fig. 2.

Fig. 4 is a detail view showing the application of a modified form of the invention.

Fig. 5 is a vertical sectional view taken on the line 5—5, Fig. 6.

Fig. 6 is a horizontal sectional view taken on the line 6—6, Fig. 5.

Referring to the form of the invention shown in Figs. 1, 2 and 3, the numeral 10 designates a foot rest which may be of any desired size and configuration and constructed of any suitable material, but is preferably of a substantially triangular shaped form to form a rest for the feet. This rest is low and is provided with a casing 11 therein of a size somewhat smaller than the outer casing and the bottom 12 of the outer casing also constitutes the bottom of the casing 11. The walls of the casing 11 co-operate with the walls of the casing 10 to form a closed water space therebetween and an inlet 14

is provided by means of which the water chamber may be filled. The inlet is provided with a removable cap 15 and the opening of the inlet, where it extends into the casing 10, is spaced from the highest point of the casing 10 so that when the water chamber is filled with water an air chamber 16 will be formed above the water to permit of the accumulation of steam should the water be hot enough to generate steam and also to permit of the expansion of the water in the event that it should freeze.

An overflow pipe 17 is also provided in the water chamber and the inlet of the overflow terminates in the space 16 at a higher elevation than the water inlet opening 14.

A safety valve 18 may also be provided in the casing 10 and which valve leads from the space 16.

Leading into the casing 11 is a pipe 19 which has communication with the exhaust pipe of the engine and a suitable controlling valve may be provided for controlling the inlet of the exhaust gases from the exhaust pipe into the casing 11.

The casing 11 is also provided with an outlet pipe 20 so that the exhaust gases passing through the pipe 19 will circulate through the casing 11 and out of the pipe 20, and thereby heat the water in the water chamber 13. The overflow pipe 17 may be arranged in any suitable position and may be constructed in any suitable manner but is preferably provided with a portion 21 in the form of a small flexible metal tube adapted to be coiled around the pipe 20. This overflow pipe serves the function of permitting the steam or vapors which may be generated in the water chamber to pass out of the space 16. The inlet of the overflow pipe is arranged in such a position that any motion given to the water in the water chamber by the movement of the vehicle, will prevent the water from swinging over the inlet of the overflow pipe.

The heater may be held in any suitable manner preferably by means of feet or brackets 22 for securing the heater to the floor.

In the form of the invention shown in Figs. 4 to 6, the heater is shown as being embedded in the floor so that the top 23 thereof will be flush with the floor of the vehicle. In this form of the invention, a suitable support 24 preferably in the form of an open box depends below the floor of the

vehicle and opens through the floor thereof. Arranged within this support is a casing 25 having a closed water chamber 26 provided with a fill inlet 27 and an overflow outlet 28, all similar in construction to the form shown in Figs. 1 to 3. The inlet pipe 29 corresponds with the inlet pipe 19 and the outlet pipe 30 corresponds with the outlet pipe 20. In this form of the invention 10 the top of the water chamber 26 is spaced below the top 23 of the heater and shutters 31 similar to the ordinary register shutters may be provided for shutting off the supply of heat.

15 In this form of the invention the exhaust gases enter the pipe 29 and flow through the chamber 32 and out of the pipe 30. During this passage through the chamber, the water in the water chamber 26 is 20 heated and the heat generated thereby is discharged into the vehicle and such discharge is controlled by the shutters or dampers 31. If desired heat insulating material 33 such as asbestos or the like may 25 be provided either on the inside of the box 24 or the outside of the heater 25.

A suitable valve 34 may be provided in the bottom of the box 24 and is adapted to be opened to permit outside air to flow into 30 the box and around the heater and through the register or grating 23 when desired. When it is not desired to permit outside air to enter, this valve 34 is closed. While no 35 operating mechanism is shown for the valve 34 it is to be understood that it may be operated in any suitable manner.

The inlet of the overflow pipe 28 is located at a higher elevation than the top of the fillpipe 27, and which latter may be provided with a removable closure 35.

While the preferred forms of the invention have been herein shown and described it is to be understood that various changes may be made in the details of construction and 45 in the combination and arrangement of the several parts without departing from the spirit of this invention.

What is claimed as new is:—

1. In a heater for automobiles, the combination of an outer casing constituting a foot rest and heat radiator element, an in-

ner casing within the outer casing providing a water chamber between the casings, said chamber being closed to the interior of the inner casing and adapted to form a closed non-circulating water space, means for introducing a supply of water into the space, and means for circulating a heating medium through the inner casing.

2. In a heater for automobiles, the combination of an outer casing constituting a foot rest and heat radiator element, an inner casing within the outer casing providing a water chamber between the casings, said chamber being closed to the interior of the inner casing and adapted to form a closed non-circulating water space, means for introducing a supply of water into the space, means for circulating a heating medium through the inner casing, and means for controlling the circulation of said heating medium.

3. In a heater for automobiles, the combination of an outer casing constituting a foot rest and heat radiator element, an inner casing within the outer casing providing a water chamber between the casings, said chamber being closed to the interior of the inner casing and adapted to form a closed non-circulating water space, means for introducing a supply of water into the space, means for circulating a heating medium through the inner casing, and an overflow passage for the said water chamber.

4. In a heater for motor vehicles, the combination of a radiator, said radiator embodying a closed non-circulating water chamber, means for circulating the exhaust gases from the engine through the heater out of commingling relation with the water in said chamber to heat the water, and an overflow pipe for the water chamber, said pipe leading from a point above the normal level of the water in the chamber.

In testimony whereof I have signed my name to this specification, in the presence of two subscribing witnesses, on this 6th day of December, A. D. 1916.

ROY M. DEAN.
